UNITED STATES PATENT OFFICE

GEORGE F. DUNN, OF BROCKTON, MASSACHUSETTS, ASSIGNEE TO WILLIAM B. ARNOLD,
OF NORTH ABINGTON, MASSACHUSETTS.

SHANK-STIFFENER.

No. 861,166.

Specification of Letters Patent. Patented July 28, 1907.

Application filed January 24, 1905. Serial No. 242,487.

To all whom it may concern:

Be it known that I, GEORGE F. DUNN, a citizen of the United States, residing at Brockton, in the county of Plymouth and State of Massachusetts, have invented 5 an Improvement in Shank-Stiffeners, of which the following description, in connection with the accompanying drawings, is a specification, like letters on the drawings representing like parts.

My invention is an improved shank stiffener having 10 for its object the provision of means for insuring the permanence of the arch at the shank of the boot or shoe, with material light in weight, and extremely neat appearance.

One of the common forms of shank stiffener is a strip 15 of sheet steel, originally flat, which is bent to the shape of the arch required, but this requires an undue weight and thickness of material as well as high grade steel, and accordingly another form of shank has been employed consisting of two thinner pieces of metal arched 20 with slightly different curves and fastened to each other at their ends, but this also is heavy, expensive and cumbersome. I have found that I can meet the requirements of light weight, thin material, slight cost, and the avoidance of creases and ridges in the inclosing 25 leather of the shank, by providing a thin steel or similar stiff metal shank arched properly and provided along its middle with a longitudinal curve arched upwardly so that the stiffener has its greatest length along its longitudinal center which is also the highest portion of the 30 stiffener, the metal depending slightly from said central portion toward the opposite edges of the stiffener which are curved back upwardly more or less sharply for the greater portion of the length of the stiffener.

My invention will be further understood from the 35 following description taken in connection with the accompanying drawings.

In said drawings, Figure 1 is a top plan view of my improved shank stiffener; Fig. 2 is a view thereof in side elevation partly broken away for clearly illustrating 40 the construction; and Fig. 3 is a transverse sectional view taken on the line 3-3 Fig. 1.

The shank stiffener *a* is preferably made of thin steel having proper thickness and temper for the rough usage and continuous work required of it. The opposite ends 45 *a'* are flat or plane and preferably perforated in usual manner at *a''*. Just behind these perforations the metal is upwardly bent longitudinally along its central portion as indicated at *a'* and thence the metal strip depends at the opposite sides *a'* of said central longitudinal upward curve toward the edges. The metal is 50 thence curved back or upwardly at its edges as indicated at *a''* to about the height of the central upward longitudinal curve, the edge curve, however, being quite sharp and short, while the central upward curve

is gradual and broad as clearly shown in Fig. 3. This 55 improved shank stiffener is arched from end to end, as shown in Fig. 2, to correspond to the hollow of the foot and the shank of the shoe, being stamped or struck up with all its curvatures and arching simultaneously so that the metal is expanded or stretched in the process 60 of formation.

In use, I have found that a shank stiffener thus formed may be very thin and light. It is inserted and secured in the shank of a boot or shoe in the same manner as heretofore, and yet, notwithstanding the fact 65 that it has a longitudinal hollow or slight depression extending centrally along its under side, the upwardly curved edges and thin light construction prevent the formation of any noticeable creases or central ridge along the longitudinal middle of the boot or shoe shank. 70

The particular construction which I provide stretches the metal as already stated, and produces a construction in which the outside layer of leather presses the sharply bent-up edges *a'* into the inside layer of leather 75 at such an angle that it is practically impossible for the shank to break down or give out under ordinary walking strains. The shank is not merely reinforced and strengthened because of its being bent as would be the case with a piece of corrugated metal, but the particular location and arrangement of the bends, the outer upward bend being sharp or abrupt and the inner bend being gradual, the outer bend being short, and the inner bend being long, and the inner bend being formed simultaneously with the formation of the entire shank and not extending to the ends, whereby said formation 80 produces a stretching and expanding of the metal, all 85 produces a stretching and expanding of the metal, all conduce, in connection with the upper and lower layers of leather which embrace the shank above and below, to produce the advantageous results described.

Having described my invention, what I claim as new, 90 and desire to secure by Letters Patent of the United States, is:—

An article of manufacture, a shank stiffener, consisting of a thin metal strip having flat ends and arched thence from one of said flat ends to the other to conform 95 to the shank of a boot or shoe, the intermediate portion of the stiffener between the sides and ends having the metal stretched and expanded upwardly in a broad, low, longitudinal bulge or upward bend, highest along the longitudinal center of the stiffener and converging into the plane surfaces at the ends thereof, said stiffener at its side edges having short, upward bends extending to approximately the height of said longitudinal bulge or bend for engaging 100 approximately perpendicularly the adjacent surface of the inner layer of leather at their extreme edges. 105

In testimony whereof, I have signed my name to this specification, in the presence of two subscribing witnesses.

GEORGE F. DUNN.
